(57) **CLAIM**

The ornamental design for a storage pouch, as shown and described.

DESCRIPTION

FIG. 1 is a left side elevational view of a storage pouch showing my novel design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a front perspective view thereof;

FIG. 8 is a front perspective view thereof with the flap in a lowered position and a computer device stored in the pouch; and,

FIG. 9 is a front perspective view thereof in a folded position.

The drawings have been lined to indicate that the storage pouch is made from cloth or fabric material.

The broken lines in FIG. 8 depicting the computer device illustrate environment which forms no part of the claimed design.
